attys.

UNITED STATES PATENT OFFICE.

MILTON P. McLAUGHLIN, OF WAKEFIELD, MASSACHUSETTS, ASSIGNOR OF ONE-THIRD TO FRANK F. COGGIN, OF MEDFORD, MASSACHUSETTS, AND ONE-THIRD TO RICHARD P. WHITCHER, OF MELROSE, MASSACHUSETTS; JULIE V. COGGIN AND FRANK M. COGGIN EXECUTORS OF THE SAID FRANK F. COGGIN, DECEASED.

GREASE-CUP PLUG.

Application filed December 18, 1923. Serial No. 681,377.

To all whom it may concern:

Be it known that I, MILTON P. McLAUGHLIN, a citizen of the United States, residing at Wakefield, in the county of Middlesex and State of Massachusetts, have invented new and useful Improvements in Grease-Cup Plugs, of which the following is a specification.

This invention relates to grease-cups employed to confine a lubricant, and particularly a relatively hard grease, on a moving part of a machine, such as the connecting-rod of a locomotive, or other part subjected to vibration. A cup of this character is provided by a cavity in the moving part, having a female screw thread, and a removable plug, having a male thread detachably engaged with the female thread. When the cup is carried by a part, such as a connecting-rod, connecting the driving wheels of a locomotive, the plug is often accidentally disengaged by the movements of the cup.

It is the object of my invention to provide a simple and effective means for confining the plug in such manner as to prevent liability of accidental disengagement and loss of the same, said means being applicable to an existing plug by a slight alteration of the latter.

Of the accompanying drawings forming a part of this specification,—

Figure 1 is a sectional view of a grease-cup including a plug embodying my invention.

Figure 2 is a sectional view, showing the plug removed from the cup.

The same reference characters indicate the same parts in all of the figures.

A grease-cup plug 12 embodying the invention, has a male screw thread, adapted for engagement with the female thread of a cup carried by a moving part, such for example, as a portion 14 of a locomotive connecting-rod, the cup being provided by a cavity 13 formed in the portion 14.

The plug 12 includes a body having at its inner end a recess 15, forming the internal surface of an annular wall 19, on which the male screw thread is formed, and a wrench-engaging portion 16. The plug as thus far described, is a well known adjunct of a locomotive connecting-rod.

In carrying out my invention, I modify the plug by providing it with a transverse orifice 20, extending through the wall 19, and with a confining socket 20^a in the inner surface of said wall. With the plug thus modified, I combine a confining member including a resilient bowed portion 18, having a shorter end portion 17^a, formed to engage the socket 20^a and a longer end portion 17, formed to extend through and project from the orifice 20, as shown by Figure 2. The confining member is sprung into the recess, the socket 20^a, and the orifice 20, and is preferably made by bending a length of suitably resilient wire, which may be brass, although steel or other wire may be employed. The closed end of the socket 20^a which is diametrically opposite the orifice 20, constitutes an abutment on which bears the shorter end portion 17^a. The bowed portion 18 is tensioned by the operation of springing the confining member into said recess, socket and orifice, so that its longer end portion 17 normally projects from the male screw thread, and is adapted to automatically and yieldingly engage the female thread and exert a limited pressure on the latter, at one side only of the plug. This limited pressure is sufficient to prevent accidental rotation of the plug, without excessively resisting the turning of the plug to insert and remove it.

The resilience of the bowed portion 18 is such that when the plug is removed from the cup, the outer end of the end portion 17, projects outwardly from the male thread, as shown by Figure 2. When the plug is screwed into the cup, as shown by Figure 1, the end portion 17 is pressed against the female thread of the cup with a sufficient force to prevent accidental rotation of the plug, while permitting an unscrewing rotation thereof by the application of considerable force.

The bowed portion 18 may be compressed by any suitable means to permit its insertion in the cavity 15, said portion, when released in the cavity, expanding to engage the confining member with the orifice 20 and socket 20^a, so that the confining member is securely held in its operative position.

The diameter of the wire of which the

confining member is made, is such that the end portion 17 presents a flat outer end face, adapted to bear on the apex of a female thread, in the portion 13, as shown by Figure 1.

I claim:

The combination with a grease cup plug having a male screw thread adapted to engage a female thread on the wall of a grease-containing cavity, and including a recess in its inner end and having a transverse orifice and a socket in the inner surface of the annular wall of said recess, of a plug-confining member composed of a metal rod including a straight end portion

extending through said orifice and having an end face adapted to extend across and bear on the apex of the said female thread, and a resilient compressible bowed portion engaging the walls of the socket, the said member being caused, by the expansion of the bowed portion in the recess, to engage the socket and project the said end face into position to bear yieldingly on the female thread, and being removable from the plug by compression of the bowed portion.

In testimony whereof I have affixed my signature.

MILTON P. McLAUGHLIN.
